FORM FOR LINING EARTH BORINGS AND HANDLING MECHANISM THEREFOR

John G. Stupp, Pittsburgh, Pa., assignor to Blaw-Knox Company, Pittsburgh, Pa., a corporation

Application June 8, 1937, Serial No. 147,025

7 Claims. (Cl. 25—131.6)

This invention relates to forms used in the casting of concrete linings in earth borings such as tunnels and the like.

The general practice in the past, in building large conduits, and especially in lining tunnels, has been to complete the excavation a sufficient distance in advance of the concrete work to make it possible to pour concrete on the floor of the tunnel and thereafter to move forward the forms for the sides and top thereof. This method is objectionable in that it requires the support of the roof of the tunnel, by bracing or other means, long enough to permit the pouring of the floor, the setting thereof, and the subsequent placement of the forms for and the pouring of the arch. Where the tunnel roof is not secure, it is desirable to pour the concrete as soon as possible after the excavation is made, and preferably to pour an entire ring section of the lining at once.

I have invented a novel form for lining earth borings and mechanism for handling it which makes it possible to accomplish the aforementioned desideratum, and is characterized by further advantages and novel features which will be pointed out during the course of the following detailed description and specifically defined in the appended claims. In accordance with my invention, I provide a traveler having retractable, wheeled, supporting legs. When the wheels of these legs are resting on a track supported on the invert or bottom member of a form section, the traveler may be used to lower and shift the upper or arch member of a form section; but when the arch member of the form section is encased in concrete, the traveler may be supported rigidly therefrom, and the legs retracted so as to permit the moving of an invert member beneath them. While being thus shifted, the invert member, with track for the traveler permanently attached thereto, may be supported by trolleys from some portion of the traveler, for which purpose I use cantilever beams movably supported by the traveler frame, and movable trolleys supported by said beams, from which chain hoists are suspended to raise and lower the invert members. Various changes may be made in the details of the mechanism, as it is usual to design form equipment to fit the requirements of each important project, the projects being subject to very great variation in size and detail, and by no means limited to circular sections. A complete understanding of the invention may be acquired by a consideration of the following description with reference to the accompanying drawings. In the drawings,

Fig. 1 is a partial longitudinal sectional view taken through a form section showing one end of the traveler therein;

Fig. 2 is a view in end elevation with parts broken away for clearness; the left and right hand sides of Fig. 2 show parts in alternative positions; Fig. 2a is a view similar to Fig. 2 showing a modification; and

Figs. 3 through 10 are diagrammatic sectional views taken axially through the form showing the traveler in side elevation therein, illustrating the various steps in the operation of advancing a form section.

Referring in detail to the drawings, and for the present to Figs. 1 to 2, a form section 10 comprises an arch or crown member 11 and an invert member or portion 12. The arch member is hinged at 13 and 14, so it can be collapsed for passage through a similar section, as will be described in detail later. The portions of the form section are composed of spaced circumferential ribs 15 connected by longitudinal reinforcing angles 16 and sheathing plates 17. Key plates 18 are disposed at the top of the arch members, and hinged doors 19 are formed in the sides thereof to facilitate pouring around the form of a concrete lining in the bore indicated at 20. Blocks or jacks 21 are employed during this operation to prevent the form from floating. The plates 18 are removably secured in position by pins 18a.

A traveler 22 is composed of four vertical legs 23 connected by upper horizontal beams 24 and intermediate horizontal beams 25. Transverse beams 26 and 27 support a working deck 28. The legs 23 are provided with wheeled feet 29 which are adjustable vertically therein, by means of screw jacks 30 or other equivalent means. The jacks 30 are threaded through nuts 31 carried between the transverse beams 26 and engage thrust bearings 32 disposed at the upper ends of the feet 29. A manual ratchet drive 33 is provided for each screw jack.

The wheels carried by the feet 29 are illustrated at 34, and are adapted to roll on rails 35, permanently secured to beams 36 mounted in the invert portion of the form.

Additional rails 37 are carried on the beams 36, the spacing between the rails 37 being the same as that between each of the rails 37 and the adjacent rail 35.

The cross beams 26 extend outwardly beyond the longitudinal beams 25 and are provided with abutments 38 for screw jacks 39. The screws of 55

the jacks 39 engage abutments 40 near the lower ends of the arch member.

The overhanging ends of the beams 26 are provided with hangers 41 on which rolls 42 are journaled. Trolley beams 43 are movable on the rolls 42. Hold-down rolls 44 are journaled in the flanges of the hangers 41. The beams 43 are provided with trolley hoists 45. A single central trolley beam may be used if desired, instead of the two side beams, as shown in Fig. 2a.

Contractible ratchet members 46 are secured to the ends of the beams 27 and to channels 47 on the side portions of the arch member.

The manner of using the structure described above will now be explained with reference to Figs. 3 through 10.

As indicated in Fig. 3, it is usual to employ two arch members 48 and 49, and three invert members 50, 51 and 52. Fig. 3 shows the position of the traveler and the trolley beams when the concrete has been poured around the arch member 49 and the invert member 52 disposed adjacent the heading 53. This concrete for the invert or bottom portion of the lining may be poured from cars 54 (see Figs. 2 and 10) which travel along a track connected with the rails 37, and up an incline 55 to the deck 28. The concrete for the upper portion is usually placed through pipes by pneumatic pressure or by pumping. During the pouring operation, the traveler is secured to the arch member of the form by bolts 56 connecting the flanges of the beams 24 to angles 57 welded to the ribs 15. When the pouring of concrete has been completed, the incline 55 is taken down, the bolts 56 removed, and the traveler moved away from the heading by the length of one form section (conveniently about 18 feet) to about the position indicated in Fig. 4. When the traveler has been withdrawn, the heading is advanced by mucking in the usual manner. To facilitate this operation, each invert member is provided with a switch (not shown) whereby cars 58 may be diverted to either pair of rails 35, 37 in the foremost lining section. In this way, an empty car coming through the tunnel may be placed on one side of the foremost invert section, by properly manipulating the switch, so that a full car on the other pair of rails can be hauled out while the first car is being filled. The switches on the invert sections are such as to permit them to pass a car along the center rails of the invert sections behind that adjacent the heading.

After the heading has been sufficiently advanced, it is necessary to move an invert and arch member forward to constitute an additional lining section. Fig. 5 illustrates this operation. The first step is to move the trolley beams rearwardly, secure the invert member 50 to the hoists 45 therefor, and lift it. The jacks 39 are then positioned and extended sufficiently to support the traveler on the arch member 48. The feet 29 are then raised, as indicated in Fig. 6 and at the left-hand side of Fig. 2, whereupon it is possible to advance the hoists 45 and move the invert member 50 forward under the traveler to a position as indicated in Fig. 7. The feet 29 are raised by manipulating the ratchets 33. In addition to supporting the traveler on the jacks 39, it can also be secured to the angles 57 by the bolts 56.

The next operation is the collapsing of the arch member 48. The first step in this operation is to lower the feet 29 so that the wheels 34 again rest on the rails 35, as shown in Fig. 7. The jacks

39 are then released. The angles 57 remain secured to the beams 24 or, if not previously attached, are bolted thereto. The ratchet members 46 are then operated to pull the side portions of the arch member inwardly about their hinges 13 and 14. It will be understood that the concrete surrounding the arch member 48 and the invert member 51 has matured sufficiently to permit removal of the former. The ratchets 33 are then operated to permit the feet 29 to be retracted into the legs 23. Since the traveler is not supported independently of the wheels, it is lowered so that the top of the arch member 48 clears the inner flanges of the ribs in the arch member 49. This lowering of the carriage also lowers the trolley beams, but the hoists 45 can be taken up to maintain clearance between the invert forms 50 and 52.

The next step is to advance the traveler to the position shown in Fig. 8. When in that position, the invert form 50 is lowered into place, the rear edge being secured to invert form 52, and the forward edge being supported on a bulkhead 59. Intermediate supports can be placed under the invert member 50, if desired, to sustain the weight of the traveler which is next advanced, as shown in Fig. 9, after withdrawing the trolley beams. The arch member 48 is raised by operating the jacks 30, the side portions thereof being forced outwardly by the ratchet members 46. When in position, the arch member is bolted to the invert member and the form is ready to receive concrete poured therearound. This operation is illustrated diagrammatically in Fig. 10. When the pouring has been completed, the cycle is repeated. 35

It will be apparent from the foregoing description that the invention provides simple and highly efficient means for handling forms in the pouring of a concrete tunnel lining. Among the particular advantages of the construction described is the fact that it is not necessary to move the traveler any further ahead than the arch member being placed. A further advantage is that it is unnecessary to lay rail on the previously completed section to permit advancement of the form. It is necessary, of course, to lay rail to replace that on the invert member which is moved forward, but it is not necessary that this be completed before such forward movement can be effected. There is thus no delay, as the additional rail on the floor of the completed portion of the lining can be laid while the forms are being placed at the edge of the section last poured. A further advantage is that the invert section is not hinged. This permits it to be made rigid enough to safely support the traveler and form during forward movement without additional intermediate supports. 50

Although I have illustrated and described but a preferred embodiment of the invention, it will be understood that changes in the construction and mode of operation may be made without departing from the spirit of the invention or the scope of the appended claims. 55

I claim:

1. The combination with a tubular form composed of invert and arch sections, of mechanism for handling said sections including a traveling carriage having a trolley beam movable therewith and retractable wheeled supporting legs, and means for supporting the carriage on a form section in place while said legs are retracted to permit a form section to be suspended from said beam and moved under the carriage. 70

2. Apparatus for advancing a tubular form 75

- composed of a plurality of alined invert and arch sections as a lining is cast therearound comprising a traveler movable over the invert sections, said traveler having collapsible supports whereby an arch section may be lowered therewith for traveling movement, and means for supporting the traveler on an arch section whereby, on collapse of said supports, an invert section may travel thereunder.
- 5 3. Apparatus for successively advancing alined lengths of a tubular form, each including an invert and an arch section, comprising a traveling carriage having retractible legs adapted to rest on the invert sections whereby an arch section may be lowered therewith for traveling movement, and means movable on said carriage for lifting an invert section, said carriage being provided with means for supporting it on an arch section while said legs are retracted to pass 10 an invert section therebelow.
- 10 4. Apparatus for successively advancing alined lengths of a tubular form, each including an invert and an arch section comprising a traveling carriage, rails permanently secured to said 15 invert sections, said carriage having retractible wheels adapted to rest on said rails whereby the carriage may be lowered to carry one arch section through another, means whereby the carriage may be supported from an arch section and said wheels retracted to pass an invert section 20 therebelow, and means movable on said carriage for lifting an invert section and transporting it under said carriage.
- 25

5. Apparatus for successively advancing alined lengths of a tubular form, each including an invert and an arch section, comprising a traveling carriage having retractible legs adapted to rest on the invert sections, and means on said carriage for supporting an arch section in knocked-down relation for transport through an adjacent length of the form, said carriage also having means for supporting an invert section for similar movement.

5

6. Apparatus for successively advancing alined lengths of a tubular form, each including an invert and an arch section, comprising a traveling carriage having retractible legs adapted to rest on the invert sections whereby said carriage can 15 transport a knocked-down arch section, and means movable on said carriage for transporting an invert section.

10

7. Apparatus for successively advancing alined lengths of a tubular form, each including an invert and an arch section comprising a traveling carriage, legs supporting said carriage and having wheels traversing said invert sections, means for adjusting said legs relative to the carriage whereby to raise and lower the legs or carriage, 25 means for supporting the carriage on an arch section independently of said legs, and means movable on the carriage for lifting an invert section behind the arch section on which the carriage is supported, and transporting it to a 30 position ahead of said arch section.
